COMBINED STORM WINDOW AWNING
AND SCREEN

William A. Bowman, Baltimore, Md.

Application May 28, 1946, Serial No. 672,863

2 Claims. (Cl. 160—28)

1

This invention relates to building appurte-
nances and more particularly to windows to be
installed in buildings and including a screen and
combined awning and storm protector in its
assembly.

In a particular form of conventional type of
auxiliary window structure, the sash including
the pane, serves as an adjunct to the regular
window for the purpose of serving as a protector
against external weather effects. This form has
the disadvantage of being limited to that use
during the period when weather conditions re-
quire it. At other times it is removed, somewhat
laboriously, so as not to interfere with the use of
the original window. In other words the addi-
tional window structure interferes with the normal
use of the window except to allow light to
pass through and is particularly intended to con-
serve heat during the winter months.

In this invention, the object thereof is to pro-
vide a new and improved type of window struc-
ture that will avoid one or more of the disadvan-
tages and limitations of the prior art.

Another object of this invention is to provide
a new and improved type of window structure
that will protect a regular window against
weather conditions as may be desired and at other
times be manipulated so as to be out of the way.
The purpose of the manipulation being to provide
for the positioning of the structure so that air
and light effects passing through it, may be con-
trolled.

Other objects will become apparent as the
invention is more fully set forth.

For a better understanding of the invention
reference is made to the appended drawings and
the following description, wherein an outline of
a particular form is detailed by way of example
to illustrate its features. The scope of the in-
vention is indicated in the claims. In the
drawings:

Figure 1 is an outside elevation of a combined
storm window, awning and screen in closed position
embodimenting this invention;

Figure 2 is a sectional view taken along line
2—2 of Figure 1;

Figure 3 is an outside elevation of the device,
with the storm window folded upwardly and out-
wardly and drawing up the screen;

Figure 4 is a sectional view taken along line
4—4 of Figure 3, and

Figure 5 is a typical section through the clamp
lock used in this embodiment showing its method
of attaching to the hinge 19 and channel.

Similar reference characters refer to similar
parts throughout the drawings.

2

In the particular form illustrated, 10 represents
the window frame of standard rectangular con-
tour and longer vertically than horizontally.
The frame is arranged for the vertical reciproca-
tion of the sashes 14 within its guiding strips 15,
in the regular manner. The sashes are sup-
ported and balanced in any suitable manner, such
as is already known to the art. An auxiliary
window structure is mounted within the same
frame 10 and consists of the upper double window
sash 16 suspended on a hinge 17 and adapted to
swing outwardly thereon from a vertical to an
angular plane. It is also provided with a medial
hinge 11 which joins it to the lower double win-
dow sash 18 that propels and enables both sashes
to apex or jack knife outwardly as indicated. In
Figures 3 and 4 another hinge 19 is secured to
the bottom of the sash 18 and slides up and down
between guide walls 21 of channel 22 as do the
other hinges. The bar 23 of the lower sash 18 is
rested when down, on a screen box 24. There is
an automatically retractable screen 25 within the
box extending to the bar 23 and hinge structure
19 so that the raising of the sashes will pull the
screen out of the box like a curtain. The screen
will take the place of the lower sash and even the
upper sash when opened enough, and thereby
keep insects from passing through the window
space into the room. The channels 22 serve as
guides for the screen. In order to provide means
for retaining the screen 25 and sashes 16 and 18
in place when opened up, a clamp lock 26 is in-
stalled on the hinge bar 19 and operated from
the inside by set screws 20 to hold the sashes and
screen in the position selected. In the latter in-
stance the regular window has to be raised so the
user can actuate the lock clamp.

An important feature of this construction is in
the use of double panes 27 and 28 of glass or
plastic for the auxiliary window. These panes
are transparent preferably, or at least trans-
lucent. The inner pane 28 is colored differently
or made opaque, to produce a predetermined
color effect in the light reaching the regular win-
dow. There are a number of reasons for this
coloring, among which are to vary the color
effect within the room; vary its temperature and
diffuse the amount of light to reach the regular
window on its way to the room. The panes are
held by screws 29 passing through strips 30 and
31 into the sashes. A screen 32 is guided in and
attached to channels.

The raising or lowering of the sashes can vary
this effect and in doing so suit the requirements
sought by the users of the windows. The screen
32 is in place all the time and forms a stationary

obstruction to flies and dust flying through it towards the open or closed window 15. It also cooperates with the lower screen 25 as the latter is raised from the box 24 for the same purpose. When the screen 25 is entirely raised in coordination with the full raising of the sashes 16 and 18 to the converged or apexed position shown in Figure 4, it cooperates with the upper screen 32 to completely close the openings in the front window structure. This prevents the flies getting through the structure by way of the open sides. The rounded munions of the sashes 16 and 18 where they press against each other enable them to roll on one another and prevent a noticeable crack appearing during any portion of their movements during opening and closing. The spacing in between the jack-knife structure formed by the sashes 16 and 18, and the conventional sashes 15 provides a dead air space that establishes a cushion in between them when the sashes 16 and 18 are opened and closed. This preventing the panes from collapsing under the sudden variations in air pressure thereon, during these movements. The screen 32 being on the sash 21 strengthens it and reinforces it to meet extraordinary stresses such as those induced by wind or snow on the sash 16.

While but one general form of the invention is shown in the drawings and described in the specifications it is not desired to limit this application for patent to this particular form, as it is appreciated that other forms of the invention could be made that would use the same principles and come within the scope of the appended claims.

Having thus described the invention, what is claimed is:

1. A window construction comprising a frame, a window in said frame, a second window in said frame outwardly of said first named window, said

second window comprising an upper sash and a lower sash, hinge means securing the upper edge of said upper sash to said frame, guiding means for slidably mounting the lower edge of said lower sash in said frame, pivot means securing the lower edge of said upper sash to the upper edge of said lower sash, whereby said sashes may protrude outwardly and angularly from said frame, a box disposed transversely across the frame in front of said first named window, a retractable screen of flexible fabric housable in said box, means for securing the free edge of said screen to the lower edge of said lower sash whereby said screen and sash will move together, and a stationary screen in said frame between said upper sash and said first mentioned window.

2. A window construction as set forth in claim 1, means for locking said sashes in any selected protruding position, said sashes including a plurality of panes to provide air spaces therebetween.
